Patented June 17, 1902.

F. THOUROT.

COOLING ATTACHMENT FOR INTERNAL COMBUSTION MOTORS.

(Application filed Jan. 29, 1902.)

(No Model.)

UNITED STATES PATENT OFFICE.

FREDERICK THOUROT, OF NEW YORK, N. Y., ASSIGNOR OF ONE-HALF TO
WILLIAM KAMMEYER, OF JERSEY CITY, NEW JERSEY.

COOLING ATTACHMENT FOR INTERNAL-COMBUSTION MOTORS.

SPECIFICATION forming part of Letters Patent No. 702,750, dated June 17, 1902.

Application filed January 29, 1902. Serial No. 91,777. (No model.)

To all whom it may concern:

Be it known that I, FREDERICK THOUROT, a citizen of the United States, residing in New York, borough of Manhattan, and State of New York, have invented certain new and useful Improvements in Cooling Attachments for Internal-Explosion Motors, of which the following is a specification.

This invention relates to certain improvements in cooling attachments for internal-explosion motors; and its object is to cool the piston and the inner walls of the motor-cylinder, as well as the crank-case of the same, said attachment being adapted to be applied to motors already in use and also to new motors.

The invention consists of a cooling attachment that is adapted to be applied to internal-explosion motors, said attachment comprising a hollow body having an enlarged upper end formed with a laterally-extending portion, said portion having a screened opening in the underside thereof, a connecting-tube provided at the lower end, and an internal baffle-plate 25 arranged opposite the inner end of said tube, as will be more fully described hereinafter and finally pointed out in the claims.

In the accompanying drawings, Figure 1 is a side elevation of an internal-explosion motor with my attachment in position thereon. Fig. 2 is a vertical section of the attachment drawn on a larger scale. Fig. 3 is a vertical transverse section on line 3 3, Fig. 2; and Fig. 4 is a plan view of the same.

Similar letters of reference indicate corresponding parts.

Referring to the drawings, A represents the crank-case of an internal-explosion motor of any approved construction, such as used for automobiles, motor-cycles, and the like. The crank-case A is provided with an opening a at any suitable point where it is desired to apply the cooling attachment C. The cooling attachment C consists of a hollow body D of 45 tapering shape in front elevation and of rectangular transverse section and is provided with an enlarged upper end D', formed with a laterally-extending portion that is provided with a horizontally-disposed under surface d, 50 which has a screened opening d'. At the lower contracted end of the hollow body D is

provided a rearwardly-extending connecting-tube C', that is exteriorly threaded, so as to be secured in the screw-threaded opening a of the crank-case. On the front face of the 55 hollow body is internally arranged the inclined baffle-plate e, strengthened by the web e'. The baffle-plate is disposed at the lower end of the hollow body opposite the inner end of the connecting-tube C', and being somewhat inclined serves to arrest the discharge of oil through the attachment from the crank-case by the forceful passage of air therefrom.

The screen at the outgoing end of the attachment serves for preventing the ingress 65 of dust and other impurities to the interior of the motor, so that a smooth and easy working of the same is obtained, while by the baffle-plate at the lower portion of the funnel-shaped body the oil is returned by the 70 suction action of the motor to the interior of the crank-case without being blown out through the attachment by the downstroke of the piston.

The attachment is applied in upright position on the crank-case of the motor whatever be the position of the same, so as to produce its proper functioning. It enables the hot compressed air to pass out of the motor on the downstroke of the piston and also serves 80 to draw in the cool exterior air, so as to cool the interior of the cylinder as well as the piston, the whole being a comparatively simple and cheap construction which can be readily applied to new motors as well as to motors 85 already in use.

Having thus described my invention, I claim as new and desire to secure by Letters Patent—

1. A cooling attachment for internal-explosion motors, consisting of a hollow body having an enlarged upper end formed with a laterally-extending portion, the under side of said laterally-extending portion being provided with a screened opening, and a connecting-tube provided at the lower end of said hollow body, substantially as set forth.

2. A cooling attachment for internal-explosion motors, consisting of a hollow body having an enlarged upper end formed with a laterally-extending portion, said laterally-extending portion having a screened opening in

the underside thereof, a connecting-tube projecting from the lower end of said body, and a baffle-plate arranged in said body at the lower end thereof, opposite said connecting-
5 tube, substantially as set forth.

3. The combination, with the casing of an internal-explosion motor provided with a suitable discharge-opening, of a cooling attachment consisting of a hollow body having an
10 enlarged upper end provided with a screened opening, a connecting-tube at the lower end

of said body, and an internal baffle-plate arranged opposite the inner end of said connecting-tube, substantially as set forth.

In testimony that I claim the foregoing as 15 my invention I have signed my name in presence of two subscribing witnesses.

FREDERICK THOUROT.

Witnesses:

PAUL GOEPEL,
C. BRADWAY.
